UNITED STATES PATENT OFFICE.

HENRY I. HAWXHURST, OF SIERRA MADRE, CALIFORNIA.

GYMNAStic APPLIANCE.

Application filed November 2, 1923. Serial No. 672,401.

My invention relates to a device designed primarily to stretch the muscles of the neck and back, and to correct curvature of the spine, and to stretch the abdominal muscles 5 and the object thereof is to provide a simple and efficient device for that purpose, that can be manipulated by the person using the same with his arms outstretched thereby.

In the drawings forming a part of this 10 specification:

Fig. 1, is a front view of my appliance;

Fig. 2, is a perspective view of the head support;

Fig. 3, is a side view, slightly perspective 15 of the part shown in Fig. 2, with the head of a person shown positioned therein;

Fig. 4, shows a body strap;

Fig. 5, illustrates the use of the body 20 strap;

Fig. 6 is a front view of a modified form of head support;

Fig. 7 is a perspective view of the form 25 shown in Fig. 6 showing it positioned;

Fig. 8 is a detail of a joint shown in Figs. 25 6 and 7.

My device is attached to an elevated support, shown in the drawings as the ceiling 10, into which a screw eye 11 is fastened. A support 12, either a strip of iron or a 30 heavy strap is secured to 11. On the lower end of 12 is pivotally mounted, a pair of levers 13 and 14, to which are connected links 15 and 16. Levers 13 and 14 are connected by pivot 17, which also connects them 35 to 12. Links 15 and 16 are pivotally connected to levers 13 and 14, and are connected to each other by a hook 18. A chain 19 is connected to hook 18. On the bottom of chain 18, is secured a bail 20, in the eye 21, 40 to which are secured bars 22 and 23. Strap 24 has loops in the ends thereof which are passed over the ends of bars 22 and 23. Strap 25, has like loops for a like purpose. Strap 24, may be positioned on bars 22 and 45 23, to pass beneath the chin of the user as shown in Fig. 3, and strap 25 would be positioned on the bars to engage the back of the head as shown in said figure when the device is to be used. A chin pad 26, may be attached to strap 24.

Other means can be used to connect the ends of the levers to the person of the user such as cords connected to a head or arm piece. When the device is positioned on the 55 wearer for use the levers are in their open position as shown in Fig. 1, and the outer

ends of levers 13 and 14, are provided with hooks 27, that are removably secured in holes 28. I have shown 3 holes in each lever to enable the user to adjust the hooks to give different leverages. A cord 29, having an adjusting clip 30, is mounted in each hook connected to levers 13 and 14. Hand knobs 31, may be secured upon the ends of cords 30. Cords 29, could be omitted if the levers are 60 positioned so as to be grasped by the hands of the user.

It will be understood that when the apparatus is positioned for use, that the user stands upright on the floor, and grasps the 70 knobs with his hands, his arms being raised as shown in Fig. 5, and the levers as shown in Fig. 1. By pulling on the cords, he can exert a pulling effect to stretch his spinal column, being able to lift his body from the 75 floor. This will put considerable strain on the neck, and it may be desired not to have great strain on the neck, but to have the stretch upon the body below the shoulders. In such case, bail 20, would be disconnected 80 from chain 19, and arm straps 32, would be substituted therefor. Straps 32, would be placed under the arms as shown in Fig. 5, when the body could be stretched by pulling on the cords. Straps 32 could be used under 85 the chin and back of the head if desired, but I prefer the use of the bail and connected parts when the neck is to be stretched.

The stretching of the vertebrae also stretches the muscles of the abdomen. It 90 will be observed that in the operation of the device, the user has his arms spread apart, thereby expanding the chest and giving free movement to the lungs and other internal organs.

In the modified form of head support shown in Figs. 6 and 7, a U-shaped yoke 33 has threaded thereon a T-fitting 34 which is revoluble thereon. In fitting 34 is secured a curved bar 35 that extends upwardly and forwardly, when positioned for use as shown in Fig. 7, and has secured on the end thereof a T-fitting 36 in which is mounted a cross bar 37. On the outer ends of bar 37 are short eye rods 38 which have eyes at each 95 end. The upper eyes are rockable on bar 37 and in the lower eyes are secured the back strap 39. Front cords 40 pass through the lower eyes of rods 38 and are provided with adjusting catches 41 for adjusting the 100 distance between the lower eyes of rods 38 and the ends of yoke 33. A piece of strong 105 110

canvas 42 forming a chin strap has the ends turned back and sewed to the body to enable the ends of yoke 33 to be passed therethrough and thereby position the chin strap 5 on the yoke. The center of strap 42 may be provided with a pad 43. An eye 44 is secured to the upper end of bar 35 and is engaged by chain 19 when the device is positioned for use. Fitting 34 has a slit 45 10 therein through which passes a screw 46 that screws into yoke 33 to prevent bar 35 rocking too far. In this form of head support the head of the user is passed into yoke 33 with the chin above strap 42. Strap 15 39 is then positioned to engage the back of the head as high up as can be done without causing it to slip off. Cords 40 are then adjusted to bring strap 42 up under the chin when the head support is positioned 20 for use, as shown in Fig. 7. The device is used as before described. In this form it will be observed that the head support by adjusting cords 40 will fit upon a small or a large head equally well.

25 It will be observed that chain 19 could be attached to some independent support, as by being made longer to the ceiling. In such case by grasping bars 22 and 23 with the hands the spine could be stretched and the 30 body swung in various directions, which is of great benefit in correcting curvature of the spine.

Having described my invention, I claim:

1. A gymnastic apparatus comprising a 25 pair of levers; means secured to the connecting pivot of the levers to attach them to a support thereabove; links connected to said levers and to each other; means secured to the connecting pivot of the links to engage the person of the user; and means connected to the outer ends of the levers to enable the user to operate the levers, whereby portions of the body of the user may be stretched.

45 2. A gymnastic apparatus comprising a pair of levers pivoted together near the

ends thereof; supporting means connected to said levers at their pivoted connection; a pair of links pivotally connected together and to the shorter ends of the levers; means 50 connected to the links at their pivoted connection to engage the person of the user; and means connected to the outer ends of the levers adapted to enable the user to operate the levers, whereby portions of the body 55 of the user may be stretched.

3. A gymnastic apparatus comprising a pair of levers pivoted together near the ends thereof; supporting means connected to said levers at their pivoted connection; a pair of 60 links pivotally connected together and to the shorter ends of the levers; a chain connected to the links; a bail connected to the chain; bars mounted in the ends of the bail; and straps mounted on said bars.

65 4. A gymnastic apparatus comprising a pair of levers pivoted together; means connected to the pivotal connection of the levers adapted to support and suspend the same; and means connected to one end of each 70 lever adapted to be secured upon the person of the user, whereby the user may operate the levers to stretch portions of his or her body.

5. A device of the character described 75 comprising an adjustable head support formed of a yoke; a curved bar rockably secured upon said yoke intermediate its ends; a transverse bar mounted upon the end of the curved bar; a strap connected to said 80 transverse bar; a chin strap mounted upon said yoke; and adjusting cords connected to the ends of said yoke and to the ends of said transverse bar, in combination with means to suspend said support, and other means to 85 operate the same substantially as shown and described.

In witness that I claim the foregoing I have hereunto subscribed my name this 10th day of October, 1923.

HENRY I. HAWXHURST.
